INVENTOR

Ernst T. M. Boenke

UNITED STATES PATENT OFFICE.

ERNST T. M. BOENKE, OF NEW YORK, N. Y.

NECKTIE-FASTENER.

SPECIFICATION forming part of Letters, Patent No. 282,153, dated July 31, 1883.

Application filed May 10, 1883. (No model.)

To all whom it may concern:

Be it known that I, ERNST T. M. BOENKE, a citizen of the United States, and a resident of New York city, in the county of New York and State of New York, have invented certain new and useful Necktie-Bow Fasteners, of which the following is a specification.

The object of my invention is to provide a new and improved device for holding a necktie-bow or scarf in place on the collar.

The invention consists in a button having a tubular shank open at the outer end, and adapted to receive a shank or pintle projecting from the rear side of the bow or scarf, which tubular shank is passed through the button-holes of the shirt and collar from the inside toward the outside.

In the accompanying drawings, Figure 1 is a front view of the button with the tubular shank, showing the same passed through the button-holes of a shirt and collar. Fig. 2 is a rear view of a necktie-bow provided with the shank or pintle adapted to be passed into the tubular shank of the button. Fig. 3 is a longitudinal sectional view of the necktie-bow or scarf fastener, showing it held in place on the shirt and collar, which, with the bow, are shown in cross-section. Fig. 4 is a side view of the button provided with the tubular shank.

Like letters indicate like parts.

A button-head, A, of the usual construction, is provided with a tubular shank, B, which is open at the outer or free end, and preferably has a bead formed on the outer edge to prevent the edge of the shank from cutting or mutilating the edges of the button-holes in the shirt and collar. The said tubular shank can be made circular in cross-section, but is preferably flattened to prevent the pintle, stem, or shank C, which is passed into the same, from turning therein, the said stem or shank C also being flattened to fit into the tubular shank B.

The stem, pintle, or shank C is fastened to

and projects from a plate, D, fastened in some 45 suitable manner to the back of the necktie-bow or scarf E; or the stem or pintle C can be fastened to the rear side of the bow in any other suitable manner.

The tubular shank B is passed through the 50 button-holes of the shirt F and collar G from the inside toward the outside, so that the open end of the shank will be outward. The stem or pintle C is then passed into the tubular shank, and will be held therein by friction, 55 thus holding the bow in place. The necktie-bow or scarf fastener thus also serves as a collar-button.

By means of the above-described device the necktie-bow or scarf can be fastened or removed very easily and rapidly.

It is evident that without deviating from the spirit of my invention the tubular shaft can be fastened on the necktie-bow or scarf, and the stem or pintle can be secured to the button- 65 head, which may be of any desired shape.

The tubular shank B is slotted longitudinally to increase its spring-power.

The scarfs provided with my improved fastener are not to have a neckband.

I do not claim, broadly, a button having a tubular shank on one head, and a pintle fitting into the said shank and secured to the other head.

Having thus described my invention, what I 75 claim as new, and desire to secure by Letters Patent, is—

The combination, with a necktie-bow or scarf having an attaching-plate secured to its rear portion, and a button-shank projecting 80 therefrom, of a removable button-head and tube adapted to co-operate with said shank, all substantially as set forth.

ERNST T. M. BOENKE.
